UNITED STATES PATENT OFFICE.

MATHEW J. BURKEL AND LOUIS P. FOSNOT, OF AURORA, ILLINOIS.

VALVE-SPRING-LIFTING DEVICE.

Application filed October 12, 1922. Serial No. 594,017.

To all whom it may concern:

Be it known that we, MATHEW J. BURKEL and LOUIS P. FOSNOT, citizens of the United States, and residents of Aurora, county of 5 Kane, and State of Illinois, have invented certain new and useful Improvements in Valve-Spring-Lifting Devices; and we do hereby declare that the following is a full, clear, and exact description thereof, reference being had to the accompanying drawings, and to the letters of reference marked thereon, which form a part of this specification.

This invention relates to improvements in 15 valve spring lifting devices and consists of the matters hereinafter described and more particularly pointed out in the appended claims.

This invention relates especially to a valve 20 lifting tool of the type shown in an application, No. 483,685, filed by us on July 11, 1921. The object of the present invention is to further improve and simplify a tool of the kind, whereby its manufacture and assembly 25 is simplified; its efficiency is increased; and whereby the opening movement of the jaws may be arrested at variable distances between them and the jaws will become automatically locked in position and 30 yet will be capable of instant and easy release when the work on the valve is completed.

The novel tool is of simple and economical construction and may be made of stamped 35 parts which are quickly and easily assembled. The many advantages of the improved tool will appear as we proceed with our specification.

In the drawings:—

40 Fig. 1 is a view representing the improved valve spring lifting device in side elevation with the jaws in approximately closed relation.

Fig. 2 is a top plan view of the device.

45 Fig. 3 is a view representing a longitudinal central section through the device in a plane indicated by the line 3—3 of Fig. 2.

Figs. 4 and 5 represent transverse sections 50 through the device in planes indicated respectively by the lines 4—4 and 5—5 of Fig. 3.

Fig. 6 is a horizontal partial section through the device in a plane indicated by the line 6—6 of Fig. 3.

55 Fig. 7 is a detail plan view of a bit used in one of the jaws of the device.

The tool comprises in general two hand lever members pivoted together and adapted to be operated by one hand in the manner of the ordinary pliers; a pair of opposed jaw members; each carried by and operated by one of the hand lever members, means carried by each hand lever member and connected to its associated jaw member for maintaining the jaws at all times in parallel relation; and a trigger-controlled, automatic locking mechanism adapted to lock the jaw members against closing movement at a plurality of variable distances apart.

Referring now to that embodiment of the 70 invention illustrated in the drawings:— 10—10 indicate the opposed jaw members, each provided with a bifurcated jaw 11 adapted to embrace the valve stem and having a flat part 12 for engagement beneath 75 the valve spring, with an approximately semi-circular upright shoulder 13 spaced back from the edge of the flat part for embracing the peripheral body of the spring.

The body 14 of each jaw member is a 80 straight, hollow bar, as shown, with upright, longitudinally extending side flanges 15. The jaw member 11 preferably extends laterally at an angle to the length of the body 14, so that the tool may be inserted for 85 engagement with the valve spring at one side and back of any obstruction that may interfere with direct access. The jaw members, when made as shown, may be fabricated from the same blanks:—two forming 90 dies, however, are required.

16—16 indicate two hand lever members 95 which are similar in form to the hand levers of a pair of pliers. Each lever is a flanged hollow bar comprising a main web 16^a and depending side flanges 16^b. Said flanges 16^b are provided near the forward ends of the levers, with fulcrum parts 17—17 which extend some distance away from the web member 16^a, and which are connected together by a horizontal fulcrum pin or rivet 18. Each jaw member 10 is connected intermediate its ends, by a horizontal pin 19 to the forward end of its associated hand lever member,—this construction permitting 100 the jaw members to swing on the hand lever members so as to be caused to maintain a parallel relation no matter how the hand lever members are swung, the one upon the other.

105 To maintain the said parallel relation of the jaw members there are provided two 110

light, bell-crank levers 20—20, each pivoted by a horizontal pin 21 to one of the hand lever members and connected by a horizontal pin and slot connection at 22 to the rear 5 end of the jaw member carried by the said hand lever member. The bell-crank levers themselves are fulcrumed together on a horizontal pin 23 at a point midway between the two hand lever members and at the rear 10 of the fulcrum pin 18 of said lever. Manifestly, when the hand lever members are swung towards or away from each other, the bell-crank levers 20—20 will maintain the jaw members in parallel relation, the 15 fulcrum pin 23 of said levers moving towards or away from the fulcrum pin 18 of the lever, depending on the way said hand levers are swung and the forward end of said bell-crank levers swinging on their pin 20 and slot connection with the jaw members.

In order to lock the jaw members at different distances apart, as the hand lever members are operated to swing them apart, there are provided two engaging latch members, namely, a fixed latch member 24 and a pivoted latch member 25. The fixed latch member 24 is attached to one hand lever member and is provided with ratchet teeth 24^a. The pivoted latch member is carried 25 by the other hand lever. It is pivoted at 26 to and between the flanges 16^b of said hand lever and is provided with one or more teeth 25^a adapted to engage the ratchet teeth 24^a. The teeth are suitably inclined so that 30 the teeth of the pivoted latch member or trigger will slide over the ratchet teeth 24^a as the levers are operated to open the jaws of the teeth. A spring 27 maintains the trigger in engagement with the ratchet. 35 The trigger has a heel 28, which projects through a slot 29 in the main web 16^c of the associated hand lever member and is there provided with a finger piece or end to be engaged by the thumb or finger to release 40 the trigger when it is desired to close the jaws together.

To partially close in the ratchet teeth of the latch mechanism and to protect and prevent the fingers of the operator from being caught or engaged therein, we preferably provide plates 30—30 (see Figs. 1 and 6) which are placed on opposite sides of the space occupied by said latch mechanism. Said plates are secured in place by the bolt 50 or rivet 23, which is the fulcrum of the levers 20—20, and have their forward ends slotted as indicated at 30^a so that they may engage on the fulcrum bolt or pin 18 of the hand levers,—the slots in the ends permitting the necessary movement of said plates as they move with the fulcrum pin 23 of the hand levers, as heretofore described.

Since the tappets vary in diameter in different engines, we provide a bit 32 adapted 60 to be used with the one of the jaw members

which is brought into contact with the tappet. Such a bit is shown in plan view in Fig. 7. It consists of a flat plate cut to provide a narrow bar or stem 33 of the width between the side flanges of the hand lever 70 members and of a head 34 extending at the same angle to said narrow bar or stem as the jaws 11 extend to the length of the jaw members 10. The head 34 is bifurcated in like manner to the flat part 11 of the jaw 75 member, as indicated at 35. The bit has a notch or opening 36 which is narrower than that of the jaw member. When the notch of the jaw member is too large to engage a part of the tappet, the bit 32 is inserted 80 above the pin 19 and below the horizontal web 12 of the jaw member, with the head 34 below the jaw proper. The advantages of such a bit will be apparent.

The operation of the device is manifest 85 from the foregoing description.

While in describing the invention we have referred to certain details of mechanical construction and arrangement of parts, it is to be understood that the invention is not 90 limited thereto except as may be pointed out in the appended claims.

We claim as our invention:

1. A valve spring lifting device, comprising two parallel jaw members, hand 95 levers fulcrumed together between the said jaw members, and having short arms operatively connected to the front ends of said jaw members, and auxiliary levers fulcrumed to each other intermediate their 100 ends, each of said auxiliary levers having a pivotal connection at one end with a hand lever and a pin and slot connection with the jaw member carried by said hand lever.

2. A valve spring lifting device, comprising two parallel jaw members, hand levers fulcrumed together between and near the rear ends of said jaw members, and having short arms connected to the front ends of said jaw members, and bell-crank levers fulcrumed together at a point back of the fulcrum of said hand levers, each bell-crank lever having pivotal connection with a hand lever at its rear end and, at its forward end, a pin and slot connection with the rear end 110 of the jaw member carried by said hand lever.

3. A valve spring lifting device, comprising jaw members, hand levers carrying said jaw members, and bell-crank levers fulcrumed to each other and each operatively connecting a hand lever with a jaw member carried thereby, each jaw member being a flanged bar having a bifurcated jaw formed 120 at one end and each hand lever being a flanged bar embracing its jaw member and associated bell-crank lever, the flanges of the jaw members extending in the opposite direction to the flanges of the hand levers.

4. A valve spring lifting device, compris-

ing hand levers carrying said jaw members, and bell-crank levers operatively connecting said jaw members and hand levers to maintain the jaw members in parallel 5 relation, the jaw members and hand levers being flanged bars and the bell-crank levers being flat bars, the flanges of each hand lever embracing its associated jaw member, a rack bar fixed to one hand lever and extending 10 towards the other hand lever, and a spring controlled trigger pivoted to said other hand lever normally engaged with said rack bar and having a heel which projects through an opening provided in said 15 last named hand lever.

5. In combination with a valve spring lifting device, including a jaw member having a bifurcated jaw, a bit having a similar, bifurcated head but of different size, 20 adapted to be removably engaged below said jaw.

6. In combination with a valve spring lifting device, including a hand lever, a

jaw member having a bifurcated jaw, a pin 25 pivotally connecting said jaw member and said hand lever, and a bit having a similar bifurcated head of a different size and a stem adapted to be removably engaged between said pivot pin and said jaw member. 30

7. A valve spring lifting device, comprising jaw members, hand levers carrying said jaw members, and bell-crank levers fulcrumed to each other and each operatively connecting a hand lever with a jaw member 35 carried thereby.

In testimony that we claim the foregoing as our invention, we affix our signatures in the presence of two witnesses, this 28th day of Sept. A. D. 1922.
